CLAIM

The ornamental design for closure for packaging, as shown and described.

DESCRIPTION

FIG. 1 is a front-left perspective view of a closure for packaging according to the present disclosure.

FIG. 2 is a rear-left perspective view thereof.

FIG. 3 is a front view of the design thereof.

FIG. 4 is a rear side view of the design.

FIG. 5 is a left side view thereof.

FIG. 6 is a right side view thereof.

FIG. 7 is a top view thereof; and,

FIG. 8 is a bottom view thereof.

The broken lines depict portions of the closure for packaging that form no part of the claimed design.

1 Claim, 8 Drawing Sheets
